(57) **CLAIM**

The ornamental design for a clip for decorative lights, as shown and described.

DESCRIPTION

FIG. 1 is a perspective view of a first embodiment of a clip for decorative lights showing my new design from the top, one end, and one side;

FIG. 2 is a perspective view thereof shown from the bottom, one end, and one side, the opposite end and side being a mirror image of that shown in FIGS. 1 and 2.

FIG. 3 is a perspective view of a second embodiment of a clip for decorative lights showing my new design from the top, one end, and one side; and,

FIG. 4 is a perspective view thereof shown from the bottom, one end, and one side, the opposite end and side being a mirror image of that shown in FIGS. 3 and 4.
